DESIGN FOR A STORAGE BATTERY COVER

Robert M. Raney, Euclid, Ohio, assignor to Willard Storage Battery Company, Cleveland, Ohio, a corporation of West Virginia

Application September 25, 1946, Serial No. 133,566

Term of patent 14 years

(Cl. D26—6)

To all whom it may concern:

Be it known that I, Robert M. Raney, a citizen of the United States and a resident of Euclid, in the county of Cuyahoga and State of Ohio, have invented a new, original, and ornamental Design for a Storage Battery Cover, of which the following is a specification, reference being had to the accompanying drawing forming a part thereof, in which

Fig. 1 is a perspective view of a storage battery cover showing my new design;

Fig. 2 is a side elevational view;

Fig. 3 is an end elevational view; and

Fig. 4 is a bottom plan view.

I claim:

The ornamental design for a storage battery cover, substantially as shown.

ROBERT M. RANEY.
